UNITED STATES PATENT OFFICE

LEONARD D. CHANDLER, OF NORTH ABINGTON, MASSACHUSETTS

WELT FOR BOOTS AND SHOES

Application filed April 12, 1929. Serial No. 354,509.

The present invention relates to welting for boots and shoes.

Welting is commonly made of expensive high grade leather so that it is important that the leather stock be cut to give the greatest possible yield of welting having the required strength, width and thickness.

The present invention relates to improvements in the construction of welting whereby a substantial saving in leather may be secured, and cost in outlay for stock reduced.

In accordance with the present invention the leather stock is cut to form strips of less width than the finished welt and the width of the strip is increased the required amount by fastening to the inner edge of the strip of stock a small and inexpensive cutting of leather or a flexible strip of foreign material made of cork, felt or other compressible substance adapted to lie in the crease of the shoe. In this manner a substantial saving in leather welt stock is obtained and the material secured to the leather strip may possess properties that will cause it to fit more snugly than the usual welting in the crease of the shoe.

The invention will be best understood from the following description when read in connection with the accompanying drawings showing good practical forms thereof.

In the drawings,—

Fig. 1 is a perspective view of a piece of leather strip of less width than the finished welt;

Fig. 2 is a perspective view of a narrow strip of foreign material;

Fig. 3 is a perspective view showing the strips of Figs. 1 and 2 secured together;

Fig. 4 shows the welt of Fig. 3 having a stitch-receiving groove;

Fig. 5 is a view similar to Fig. 4 but shows a modified construction; and

Fig. 6 is a transverse sectional view through a portion of a shoe provided with the welt of Fig. 4.

In accordance with the present invention the leather stock is cut into strips 10 of less width than the desired finished welt, and the strip of welt is given the desired increased width by securing a narrow strip 11

of flexible material to the inner edge of the strip 10 as will be apparent from Fig. 3.

The narrow strip 11 may be formed of cork, felt, leather or other flexible materials and preferably is more or less compressible so that it will conform to the shape of the crease of the shoe in which it is secured and fit snugly therein. In some cases it may be desirable to use the leather cutting that is removed from the stitch-receiving groove 12 of welting, as the material 11 which is secured to the edge of the leather strip 10 to increase its width. In this manner use may be made of the small strip or cutting of leather which is ordinarily wasted in forming the groove 12. The size and shape of the groove 12 may be varied within certain limits with a view of producing a small strand of leather adapted to be secured to the edge of the strip 10 as indicated by 11 to impart the desired width to the welting. The strip 11 may have any desired shape and may be given the desired configuration either before or after it is attached to the leather strip 10, and the strip 11 may be secured to the strip 10 by adhesive cement, or other forms of securing means may be employed.

The width of the leather strip 10 is preferably such that the stitch-receiving groove 12 may be positioned some distance from the inner face of the strip 10 so that sufficient leather stock is provided adjacent this groove to withstand the pull of the stitches 13. As a result of this construction the stitches 13 need not pass through any portion of the narrow strip 11 which strip may therefore possess less tensile strength than the leather 10, and if the strip 11 is formed of cork, felt or a cutting of leather as above suggested it may be forced in the crease of the shoe more readily than the usual welting.

The welt strip constructed in accordance with the present invention preferably has the usual bevel 14 adapted to engage the shoe upper 15 against which it is held by the row of stitches 13 engaging the inner sole 16. The welt strip may be secured to a shoe the same as any ordinary welting, as will be apparent from Fig. 6.

It will be clear from the foregoing that

through the use of the present invention a substantial saving in leather welt stock is secured and the resiliency of the inner edge portion of the strip of welt may be increased so that it will fit more snugly in the shoe crease.

The features of the present invention obviously may be given various constructions and in the modification of Fig. 5 the strip of leather 10 is cut to form the integral tongue

10 17 that is bent outwardly from the welt from which it is severed to extend over the narrow strip 11 of attached material. This provides a more secure method of attaching the foreign material to the leather strip 10 and 15 covers or conceals the joint between the two strips.

What is claimed is:—

1. As an article of manufacture, a welt formed of a strip of leather stock of less 20 width than the finished welt and having its width increased by a narrow strip of cork material adhesively secured to the inner edge of the welt stock so as not to overlie the upper face of the leather strip.

2. As an article of manufacture, a welt formed of a strip of leather stock of less width than the finished welt and having an integral tongue extending therefrom, and 25 having the width of the strip increased by a strip of foreign material secured between the tongue and adjacent edge of the welt stock.

3. As an article of manufacture, a welt formed of a strip of leather stock of less width than the finished welt and having its 30 width increased by applying to the inner edge only of the welt stock a separate strip having the thickness to be added to the width of the welt stock and shaped to lie in the crease of a shoe.

4. As an article of manufacture, a welt formed of a strip of leather stock of less width than the finished welt and having its 35 width increased by applying to the inner edge only of the welt stock a separate strip of foreign material having the thickness to be added to the width of the welt stock and shaped to lie in the crease of a shoe.

In testimony whereof, I have signed my name to this specification,

LEONARD D. CHANDLER.
